UNITED STATES PATENT OFFICE.

FREDERICK L. KING, OF PROVIDENCE, RHODE ISLAND, ASSIGNOR TO
GEORGE W. DOVER, OF CRANSTON, RHODE ISLAND.

SETTING.

SPECIFICATION forming part of Letters Patent No. 729,606, dated June 2, 1903.

Application filed November 12, 1902. Serial No. 130,939. (No model.)

To all whom it may concern:

Be it known that I, FREDERICK L. KING, a citizen of the United States, residing at Providence, in the county of Providence and State of Rhode Island, have invented certain new and useful Improvements in Settings, of which the following is a specification.

My invention relates to gem-settings, and has for its primary object a means for holding gems provided with a circumferential opening and to secure this end by a simple, inexpensive, and solderless form.

To the above ends my invention consists in the structure hereinafter set forth, and illustrated in the accompanying drawings, wherein—

Figure 1 is a perspective view of the original blank from which my setting is formed; Fig. 2, a plan view of the same after it has been dapped, struck, and trimmed; Fig. 3, a section of the same on line xx of Fig. 2; Fig. 4, a plan elevation of the same after the swaging operation; Fig. 5, a section of the completed setting on line yy of Fig. 4; Fig. 6, a transverse central section of the completed setting engaging a pearl, and Fig. 7 a side elevation of the same.

Like reference-letters indicate like parts throughout the views.

My setting is constructed as follows: From a thin sheet of metal an oblong rectangular blank A is cut with projections a radiating from the four corners thereof, while two shorter projections b extend from the center of the longer margins of the blank diametrically opposite each other. (See Fig. 1.) This blank is next dapped, struck, and trimmed into the form shown in Figs. 2 and 3—that is, the blank A, including its radial projections a b , are bounded by an upturned marginal flange c . By swaging the portions of the marginal flange which bounds the sides of the blank they are folded inwardly and downwardly upon the blank A, or what is now the base or backing of the setting, and the short prongs b are forced upwardly from the folded portion or facing of the setting in a direction at right angles to the backing, and abutting against each other form a practically

single short prong above the center of the base. By the same swaging operation the prongs a are upset and their margins folded together, so that the resulting setting has the appearance of Figs. 4 and 5.

The ornament for which my setting is particularly well adapted is an imitation pearl f . This should be provided with an orifice e through its wall and its interior f filled with wax or some other penetrable material. The pearl is inserted into the setting with the prong b entering the orifice e , and the surface of the pearl is embraced by the setting-prongs a . It is evident that the ornament thus mounted is secure against rotatory or other displacement. While the filling f is not in all cases imperative, it is sometimes required when the orifice e happens to be too ample to snugly receive the prong e , in which case the prong extremity being buried in the wax the pearl is doubly insured against any movement.

Having thus described my invention, what I claim is—

1. A setting formed from a single metallic blank comprising a backing, a facing consisting of the inturned margin of the blank, a prong projecting from the edge of the inturned margin, and radial prongs upon the backing.

2. In a setting, the combination with the ornament provided with an orifice of a retaining member formed from a single metallic blank comprising a backing, a facing consisting of the inturned margin of the blank, radial prongs upon the backing and embracing the ornament and a prong projecting from the edge of the inturned margin extending into the orifice of the ornament.

3. In a setting, the combination with a hollow ornament provided with an orifice of wax within the ornament and a retaining member formed from a single metallic blank comprising a backing, a facing consisting of the inturned margin of the blank, radial prongs upon the backing and embracing the ornament, and a prong projecting from the edge of the inturned margin extending through the orifice and into the wax.

4. In a setting, the combination with a substantially spherical ornament of a base, prongs projecting from the margin of the base for retaining the ornament in contact with
5 the base, and means above the center of the base independent of the embracing prongs adapted to prevent rotation of the ornament.

In testimony whereof I have affixed my signature in presence of two witnesses.

FREDERICK L. KING.
